UNITED STATES PATENT OFFICE.

JOHN L. CHRISTENSEN, OF CHICAGO, ILLINOIS.

FIBER-BOARD BOX.

1,422,540.

Specification of Letters Patent. Patented July 11, 1922.

Substitute for application Serial No. 445,348, filed February 16, 1921. This application filed May 5, 1922. Serial No. 558,571.

To all whom it may concern:

Be it known that I, JOHN L. CHRISTENSEN, a citizen of the United States, residing at Chicago, in the county of Cook and State of Illinois, have invented a certain new and useful Fiber-Board Box, of which the following is a specification.

The invention relates to boxes or receptacles such as are commonly employed in retail selling establishments as containers for articles of merchandise. One type of such receptacles is generally known as "suit-boxes" but the invention pertains to all boxes of this general character irrespective of the particular use to which they may be put and also, in its broad aspects, irrespective of size.

Boxes of this general class now in general use are usually constructed in two separate sections and are supplied to the user in the form of flat blanks so as to occupy a minimum amount of space in shipment and in storage, and hence must be assembled by the user. My invention is directed to a box or receptacle which is capable of being made from a single sheet of fiber board or other suitable material and which while assembled at the factory is nevertheless capable of being folded or knocked down so as to permit of its shipment and storage in a flat form, occupying a relatively small amount of space more than that occupied by the flat blanks.

The primary object of the present invention is to provide a box of this character having top and bottom sections hinged together and swingable into interfitting relation with the utmost ease and facility, the operation being of a semi-automatic character in that the end walls of the respective sections are properly positioned with respect to each other through the outer side walls when the latter are grasped in a natural way to bring the sections together.

The object of the invention thus generally stated, together with other and ancillary advantages are attained by the construction and arrangement illustrated in the accompanying drawings forming part hereof wherein I have illustrated a single embodiment of the invention. I contemplate, however, that various changes in the form, construction and arrangement of the parts may be made by those skilled in the art but without departing from the spirit and scope of my invention as expressed in the appended claims.

Referring now to the drawings, Figure 1 is a perspective view of my improved box in its assembled form. Fig. 2 is a top plan view of the blank folded into the form which it occupies when it leaves the factory. Fig. 3 is a plan view of the blank from which the box is formed and having secured thereto a reinforcing strip for one wide wall of the box. Fig. 4 is a plan view of a portion of the blank used in the construction of a modified form of corner connecting means. Fig. 4^a is a fragmentary perspective view of such connecting means. Fig. 5 is a fragmentary perspective view illustrating the method of folding the blank midway between its ends in the operation of closing the box. Figs. 6 and 7 are perspective views showing the positions which the parts occupy at different stages in the operation of closing the box.

The box in its preferred form comprises an upper or top section A and a lower or bottom section B formed from a single sheet of material such as fiber board and each comprising a main wall, opposite end walls, an outer side wall and an intermediate or common side wall. Thus the upper section A comprises a main wall 8, end walls 9, outer side wall 10; and the lower section B comprises a main wall 11, end walls 12, and an outer side wall 13. An intermediate side wall 14, which it will be observed, is common to both sections, constitutes a hinge between the two sections. The corresponding end walls 8 and 12 of the two sections are preferably connected together by rectangular intermediate portions 15 which are notched at their free edges as at 16, so as to permit of a relative substantially independent swinging movement of these walls 15 with respect to each other whereby to facilitate the operation of swinging the sections into interfitting relation, as hereinafter more fully set forth. To permit the box to be folded into its flat or knocked-down form, the opposite outer side walls are scored diagonally adjacent their opposite ends as shown at 17 and 17^a.

The preferred manner of forming the various walls of the box as above set forth and as herein shown, consists in cutting and scoring a rectangular blank along longitudinal, transverse and diagonal lines, as shown in Fig. 3, to form the various portions of the blank including two rectangular

main portions 8^a and 11^a; opposite end portions 9^a and 12^a; outer side portions 10^a and 13^a; and an intermediate portion 11. Between the corresponding end portions 9^a and 12^a of the two sections are rectangular portions 15^a, and at the corners of the blank are corner portions or flaps 10^b and 12^b, respectively.

- In connecting the opposite end portions 10 9^a of the upper section with the outer side portions 10^a, the latter in the construction shown in Figs. 1 to 3, 6 and 7, is cut at its opposite ends, preferably on diagonal lines 19, and is severed from the adjacent corner 15 portions along longitudinal lines 20. By reason of the severance of the corner portions from the portion 10^a, when the end portions 9^a and the side portion 10^a are swung into perpendicular relation with respect to the main portion 8^a, the corner portions may also be swung into such perpendicular relation. Preferably such corner portions are first swung into the desired perpendicular relation and then the outer 20 side portion 10^a swung into position, so that the ends of the corner portions lie inside the opposite ends of the side portion. The specific construction which is thus provided 25 simplifies the assembling operation.
- 30 Upon the free end of the outer side portion 10^a, there is preferably provided a flap 21^a (Fig. 1) which is of a length equal to the length of said side portion at its upper edge and which is capable of being folded 35 upon a transverse score 22 inwardly and downwardly upon the inner face of the side portion 10^a to form a reinforcing or stiffening strip 21 (Figs. 2 and 3). Preferably this flap folds over the overlapping corner 40 portions 10^b. In providing for the flap 21^a, the blank is obviously made of sufficiently greater length and preferably in so doing the corner portions 10^b are also made of a correspondingly greater length, and it will 45 be observed that by reason of such increased length of the corner portions when the latter are swung into perpendicular relation to the main portion 8^a and the end portions 9^a, they serve to reinforce or brace additionally the outer side wall 10^a against vertical strains.

The several portions of the blank are secured in their folded relative perpendicular position with the corner portions flat against 55 the inner face of the outer side portion 10^a at the opposite ends of the latter and with the flap 21^a folded inwardly upon the inner face of the portion 10^a, in any suitable way. Preferably a suitable number of staples 23 60 are employed for this purpose, but it will be obvious that the parts may be secured together in any other suitable or preferred manner, as by means of a suitable adhesive.

It may be seen that the diagonal fold at 65 17 in the outer side wall 10 of the box is

facilitated by a diagonal score 24 in each of the corner portions 10^b and by the shape of the ends of the side portion 13^a cut on the lines 19 approximately coinciding with the scores 24 in the corner flaps when the latter are secured in position upon the side portion 10^a.

In forming the lower section B of the box, the corner portions 12^b are severed from the adjacent ends of the end portions 12^a 75 to permit the end portions and the outer side portion 13^a to be swung into perpendicular relation with reference to the main portion 11^a. Preferably the corner portions 12^b in this instance engage the outer faces of 80 the end portions 12^a and are secured in position by suitable means, such as staples 23^a. This arrangement of the corner portions 12^b enables the two sections of the box to be assembled more readily than would be possible if they were secured to the side wall portion 13^a, since as hereinafter set forth, the end walls of the lower section are swung into an inwardly inclined position in the assembling operation, out of alignment with 85 the end walls of the upper section. Moreover, the double thickness provided by the overlapping of the corner portions upon the outer side wall, in the case of the upper section, and upon the opposite end walls in 90 the case of the lower section, adds strength to the box, enabling it more effectively to resist vertical strains.

In order that the lower edges of the corner portions 12^b will when secured in place, present a neat and finished appearance, they may be cut at an angle so as to be inclined slightly upwardly from the corners of the box, as shown in Fig. 6. To facilitate the fold at 17^a, the outer side portion 13^a is provided with diagonal scores 24^a near the opposite ends thereof.

In Figs. 4 and 4^a I have shown another method of connecting the outer side walls with the opposite end walls. This method, while somewhat more expensive from a manufacturing standpoint, is preferable where a more rugged construction is desired. In the present instance I have shown this method of fastening the end and side 110 walls, in connection with the upper section only, although it will be apparent that such walls of the lower section may be similarly connected.

The means which I employ in this form of 120 the box comprises rectangular corner portions 10^c which are formed integrally with both the side and end walls to be connected. These corner portions are swung bodily into an upright perpendicular relation to the end walls and to the main wall, against the outer side wall and secured thereto. To this end the outer side wall is scored diagonally near each end, as at 17^c, as well as longitudinally as at 20^c, and in the operation of swinging 125 130

the corner portion into such perpendicular relation, it flexes with reference to the side wall along the longitudinal line 20° and the side wall doubles upon itself along the diagonal line 17° (Fig. 4). The corner portions may be secured in position in any suitable manner, as by means of staples 23; and they are scored diagonally at 24° as in the construction first described to enable the side walls to bend outwardly as the end walls swing inwardly flat upon the main wall.

It will be observed that when the corner portions are thus swung bodily into upright position, they constitute stays which serve to resist vertical strains and thus impart strength to the box.

The intermediate side wall 14 of the box, it will be observed would normally be only of single ply as compared with the double 20 ply construction formed by the overlapping walls 10 and 13 when the box is closed. For the purpose of strengthening this intermediate wall, there may be secured upon its inner side a reinforcing strip 25 of a length approximately equal to the length of the box. This strip is of a width slightly less than the width of the intermediate wall so as not to restrict or interfere with the swinging movements of the sections A and B into interfitting relation. The strip may be secured in position as by means of adhesive or in any other preferred manner.

The operation of swinging the two sections of the box into interfitting or closed relation from the flat form shown in Fig. 2, is substantially as follows: The operator grasps with one hand the outer side wall 10 of the upper section A, swinging it upwardly toward a perpendicular position relative to the main wall 8 while swinging the top section bodily upwardly toward the bottom section. As the side wall 10 is thus swung upwardly the connected end walls 9 are forced outwardly, (Fig. 6) and it may be observed that this latter operation is facilitated and insured by reason of the reinforcement of the side wall 10 by means of the strip 21. Through the operation of such reinforcing strip, the portion of the end wall between the diagonal folds 17 remains approximately rigid and straight. Consequently as it swings into upright position, the ends of the wall 10 beyond the folds 17 are carried into alignment, and the latter acting upon the adjacent connected end walls 9 force them into upright or perpendicular position with respect to the main wall.

At the same time, the operator places his free hand upon the outer side wall 13 of the lower section 8 and presses downwardly thereon. This tends to restrain the opposite end walls from swinging upwardly notwithstanding the upward swinging movement of the end walls 9 of the upper section. Such relative movement between the end walls 12

of the bottom section and the end walls 9 of the upper section, is permitted by reason of the presence of the notches 16 in the rectangular connecting portions 15 between the end walls 9 and 12 of the two sections, as above set forth. Now, as the upper section A is brought forwardly and downwardly over the bottom section B, the end walls 9 occupy a position into or slightly beyond perpendicular relation to the main wall 8 of the top section, and on the other hand the end walls 12 occupy an inwardly inclined relation with respect to the main wall 11 of the lower section. It will be evident, therefore, that the end walls 9 and 12 are caused to assume, in a semi-automatic manner, their proper relation with respect to each other to insure that they will not interfere as the two sections are brought together with the bottom section within the top section.

To permit the end walls 9 and 12 thus to be swung into overlapping relation, the connecting rectangular portions 15 in addition to having the notches 16 therein, are scored diagonally along lines 26 approximately in continuation of the edges of the notches. As shown in Fig. 5, as the end walls 9 and 12 are brought together, opposite triangular portions overlap forming a substantially closed joint.

As the top section in its forward and downward movement approaches the bottom section, the lower edges of the end walls 9 engage with the outer side faces of the inclined end walls 12, and the lower edge of the outer side wall 10 rests upon the upper edge of the outer side wall 13 at the opposite ends thereof. As shown in Fig. 7, these ends are inclined upwardly and inwardly from the upper ends of the diagonal scores 17 and the extreme outer corners of the lower section by reason of such inclination of the ends of the outer side wall and of the inclination of the opposite end walls, are positioned well within the upper section. In the final operation, therefore, of closing the box, it is only necessary for the operator to force the upper edge of the outer side wall 13 of the lower section inwardly from the position shown in Fig. 7 until it clears the lower edge of the outer side wall 10 of the upper section. Thereupon the two sections may be forced into telescoping relation.

If desired, the box may now be tied by a single strand 26 around the central portion thereof to maintain the two sections in closed relation, and it will be observed that the reinforcement provided by the flap 21 upon the outer side wall 10 of the upper section insures that the portions of such outer wall upon opposite sides of the cord will not bulge but will be held firmly in position against the adjacent inner wall 13; also that such outer wall will not become torn or broken by reason of the presence of the tie,

as frequently happens in boxes of this general class.

I obtain a distinct advantage in the arrangement of the corner portions so that in 5 the case of the upper section they form part of the outer side wall, and in the case of the lower section they are made rigid with the end walls. It facilitates substantially the operation of assembling the two sections, 10 and imparts strength thereto. In the case of the construction shown in Figs. 4 and 4^a, it provides vertical stays both upon the sides and the ends of the box.

It will be apparent that the box thus provided 15 is of a very advantageous character. Its simplicity enables its manufacture on an economical basis; it lends itself readily to shipment and storage in large quantities and at a relatively low cost; the entire operation 20 of assembling the box from its flat knocked-down form into closed condition, requires only a few seconds; and when the box is thus completely closed, it presents a neat appearance and is of substantial 25 strength capable of resisting heavy vertical strains.

In compliance with the statute, I have 30 illustrated and described my invention herein as embodied in a box of the preferred form. Certain details of this box are the invention of one Albert Dreyfus and myself, jointly, and claims directed to such features are contained in a copending application Serial No. 553,246 filed April 15, 1922. As to 35 the more essential features of the box, and also certain details of construction, I am the sole inventor, and these features accordingly are made the subject matter of the appended claims.

40 This application is a continuation of my prior copending application Serial No. 445,348 filed February 16, 1921; also a continuation in part of my copending application Serial No. 485,221 filed July 16, 1921.

45 I claim as my invention:

1. A box having upper and lower sections each comprising a main portion with end and side walls swingable relative to the main portion, one of the side walls being common 50 to both sections and forming a hinge therebetween, portions connecting the adjacent end walls of the two sections having notches in their free edges and scored to permit the two sections to be swung into interfitting 55 relation, and means for securing the outer side wall of each section to the adjacent end walls, the outer side wall of one of the sections having a pair of spaced scores therein along which it may bend when drawn 60 outwardly at its center so as to cause the adjacent end walls to swing inwardly.

2. A box having upper and lower sections adapted to be swung into interfitting relation, each of said sections comprising a main 65 wall with end and side walls swingable rela-

tive to the main wall, one of the side walls being common to both sections and forming a hinge therebetween, and means for connecting the side and end walls together, the connecting means for the upper section including 70 rectangular corner portions integral with and capable of flexing relative to the connecting walls, the outer side wall having diagonal scores therein adapted to permit the corner portions to be swung bodily into 75 perpendicular relation to the end walls and to the main wall, and means for securing the corner portions to the outer side wall whereby to maintain the adjoining walls in 80 normal perpendicular relation, the outer side wall for the lower section also having diagonal scores therein permitting it to bend when drawn outwardly at its center whereby to cause the connected end walls to swing inwardly. 85

3. A box having upper and lower sections each comprising a main portion and four edge portions constituting side and end walls each swingable relative to the main portion, one of the side walls being common to both 90 sections and forming a hinge therebetween, portions at the opposite ends of said common side wall constituting connections between aligned end walls of the opposite sections and having diagonal scores therein with notches 95 at their free edges whereby to permit the two sections to be swung into interfitting relation, and means for securing the outer side walls of each section to the adjoining end walls, said outer side walls having diagonal 100 scores therein adapted to permit the end walls to be swung inwardly flat upon the main portion while the outer side walls are swung outwardly into the plane of the main portions. 105

4. A box comprising two sections each having a main portion, a pair of opposite end walls and an outer side wall, a portion between the main portions constituting a hinge therebetween and forming a common 110 side wall for the box, the end walls of the respective sections being swingable with respect to the main portions independently of each other, and means for securing the outer side walls to the end walls, one of said outer 115 side walls having scores therein whereby said end walls may be positioned by the manipulation of such outer side wall so as to facilitate the operation of swinging the sections into interfitting relation. 120

5. A box comprising two sections each having a main portion, two opposed end walls and an outer side wall, a portion between the main portions forming a hinge between the two sections and constituting a 125 common side wall for the box, and means for connecting the outer side walls to the adjacent end walls, the outer side wall of one section being scored between its ends whereby when said side wall is swung out- 130

wardly with respect to its main portion the adjacent ends of the adjoining end walls are caused to swing directly inwardly so as to facilitate the operation of assembling 5 the respective sections in interfitting relation.

6. A box of the character described having upper and lower sections adapted to be swung into interfitting relation and each 10 comprising a main wall with end and side walls swingable relative thereto, one of the side walls being common to both sections and forming a hinge therebetween, rectangular corner portions integral with and 15 connecting the end and outer side walls together, one of each pair of walls thus connected being scored diagonally so as to permit such corner portion to be swung bodily 20 into perpendicular relation to the other wall and to the main wall, and means for securing the corner portions to the scored walls whereby to maintain it and the other walls in normal perpendicular relation.

7. A box comprising upper and lower sections adapted to be assembled in interfitting relation and each having a main wall with end and side walls swingable into perpendicular relation to the main wall, the outer side wall of the upper section having 25 secured at each end thereof corner portions formed integral with the opposite end walls, and the end walls of the lower section having secured thereto corner portions formed integral with the outer side wall, the outer 30 side walls of both sections having diagonal scores therein adapted to permit them to be

swung outwardly with respect to the main walls while the opposite end walls are swung inwardly over the main walls.

8. A box comprising a main wall with end 40 and side walls swingable relative thereto, rectangular corner portions integrally connecting the end and outer side walls together, one of each pair of walls thus connected being scored diagonally so as to permit 45 the corner portion therebetween to be swung bodily into perpendicular position against the other wall and secured thereto, and one of the adjoining walls being scored diagonally to permit it to be swung outwardly 50 from the main wall while the adjoining wall is swung inwardly flat upon the main portion.

9. A box having a main wall and end and side walls swingable relative to the main 55 wall and to each other, the adjoining end and side walls having a corner portion formed integral therewith, and one of the two adjoining walls being scored diagonally to permit such corner portion to be swung 60 into position against it perpendicular to the other wall, said corner portion being scored diagonally along a line substantially coinciding with the diagonal score in the scored wall to which it is secured whereby the 65 scored wall may be swung outwardly with respect to the main wall and the adjoining wall may be swung inwardly flat upon the main wall.

In testimony whereof, I have hereunto af- 70 fixed my signature.

JOHN L. CHRISTENSEN.
